UNITED STATES PATENT OFFICE.

PAUL E. MENZEL, OF NEW YORK, N. Y.

ATTACHMENT FOR RAZORS.

Application filed November 12, 1925. Serial No. 68,687.

The razor attachment of the present invention is primarily intended for supporting a Gillette blade in proper position to be sharpened by an auto-strop blade holder and strap.

An object of the present invention is to provide an attachment of this character which may be snugly supported between the usual blade clamping jaws of the auto-strop 10 razor, and which carries means for firmly supporting a Gillette blade between said jaws.

A further object of the invention is to provide an attachment of extremely simple, 15 practical construction, which may be readily removed or applied, and which will lend itself to economical manufacture.

With the above noted and other objects in view, the invention consists in certain 20 novel features of construction and combinations and arrangements of parts, as will be more fully hereinafter set forth and pointed out in the claims. The invention may be more fully understood from the following description in connection with the 25 accompanying drawing, wherein—

Fig. 1 is a top plan view showing my improved attachment in applied position supporting a blade during stropping.

Fig. 2 is a view in longitudinal section on the line 2—2 of Fig. 1.

Fig. 3 is a top plan view of the blade holder with parts broken away for clearness, dotted lines indicating the manner in which 35 the attachment is removed from the blade holder.

Fig. 4 is a perspective view of the plate 20.

In the accompanying drawings I have 40 shown the principal features of the well known type of auto-strop razor, this razor including a handle 10 mounting a guard plate 11, from the opposite ends of which arise upstanding ears 12, between which a 45 pair of parallel shafts 13, 14 are journaled. Shaft 13 carries a roller 15 between which, and the guard plate 11, a sharpening device such as a flexible strap 16 is adapted to be drawn, this strap frictionally turning the 50 shaft 13, and through the intermediacy of suitable gearing indicated at 16, controlling the movement of the shaft 14.

Mounted upon the shaft 14 is a conventional type of blade holder including a bight 55 portion 17 encircling the shaft, and a pair

of parallel spring clamping jaws 18, 19 between which a conventional auto-strop blade (not shown) is adapted to be received. Reversal of the movement of the strap acts through the gearing 16 to reverse the position of the blade holder, and consequently to throw the blade from one side of the shaft to the other, in position for proper sharpening, as will be readily understood.

The invention as thus far described is entirely conventional. The present invention is concerned with the provision of an attachment in the nature of a flat plate 20 adapted to be inserted between the blade clamping jaws 18 and 19, and to support a Gillette blade indicated at 21. As best seen in Fig. 3, the plate 20 includes the corner lugs 22 adapted to be received behind the usual spring lugs 23 formed at the edges of the spring clamping jaw 19. The plate 20 also includes an approximately semicircular or segmental extension 24 projecting beyond the free edges of the coacting clamping jaws 18 and 19, this extension being formed with a stud 25 for the reception of the central 60 opening in the blade 21.

With the attachment plate 20 in applied position and the blade 25 supported thereon, relative movement imparted to the handle 10 and strap 16 will effect sharpening of the 65 blade in the manner above described. There is no particular problem involved in removing the plate 20 from its position between the clamping jaws, since this plate at its inner edge is shaped substantially in accordance with the shape of the blades usually mounted between the clamping jaws. Upper clamping jaw 18 is formed with a tongue 26 at one end coacting with the associated lug 23, the tongue being readily 90 sprung out of the way to permit the plate 20 to be removed as indicated in dotted lines in Fig. 3.

It will be obvious that the particular shape of the extension portion 24 of the 100 plate 20 may be considerably varied, and that if desirable more than one securing lug 25 might be stamped therefrom, or otherwise made integral therewith. I find the device highly efficient however, in the form shown.

Various changes and alterations might be 105 made in the general form and arrangement of parts described, without departing from the invention. Hence I do not wish to limit myself to the details set forth, but shall con-

sider myself at liberty to make such changes and alterations as fairly fall within the spirit and scope of the appended claims.

It will of course be understood, that when the attachment is in place between the blade clamping jaws, a blade to be sharpened may be readily inserted or removed without the necessity for dislodging or removing the plate 20.

10 I claim—

1. An attachment for razors comprising a flat plate having a straight edge adapted to be received between a pair of blade clamping jaws, and including a portion adapted to extend beyond said jaws, and formed with a blade centering stud.

2. The combination with a razor including

a pair of cooperating spring clamping jaws, lugs at the opposite ends of one of said jaws, the other jaw being cut away to accommodate the lugs, of a blade supporting attachment including a plate received between said jaws and formed with projections locking behind the lugs, a portion of said plate extending beyond the edges of the clamping jaws, and means associated with said extension portion for retaining and centering a blade.

3. A device of the class described in claim 2, wherein the extension is approximately 30 segmental and formed with a stud adapted to enter an opening in a blade.

PAUL E. MENZEL.
